LOCK MECHANISM

Filed Aug. 7, 1929

UNITED STATES PATENT OFFICE

ELMER E. NEAL, OF NEW HAVEN, CONNECTICUT, ASSIGNOR TO PEERLESS HANDCUFF COMPANY, OF SPRINGFIELD, MASSACHUSETTS, A CORPORATION OF MASSACHUSETTS

LOCK MECHANISM

Application filed August 7, 1929. Serial No. 384,006.

This invention relates to improvements in lock mechanisms and particularly in means for locking the arms of handcuffs, thumbcuffs, leg irons, and devices of that character, used by officers of the law in binding prisoners. In some of its aspects it may be used as a padlock or for improvements in locking means generally. The invention will be described in the form of a handcuff and its application to thumb cuffs, leg irons, and other uses will be apparent.

The frame work of the cuff in the form chosen for purposes of illustration is made up of two spaced, parallel semi-circular arms, between which at one end a single semi-circular arm, curved in the opposite direction, is pivoted. This arrangement makes up a bracelet. The two parallel arms have a lock casing with lock mechanism between them at the ends opposite from the pivot and at the corresponding end the single arm has means engageable by a part of the lock mechanism. The latter is operable and may be set to let the single arm move in a complete circle in either direction on its pivot, or in only one direction, or locked to prevent all movement between the arms. These conditions of the cuff setting may be considered as completely unlocked, set for snapping on the wrist or single locked, and double or completely locked. The first condition is used for releasing the prisoner, the second condition for maintaining the mechanism in condition to lock on the prisoner until his wrist is actually within the bracelet arms when the mechanism is locked with the aid of the wrist, and the third condition for doubly securing the locked position of the parts.

The particular purpose of the present invention is to provide locking means in relation to any one or all of the desired conditions of mechanism of the kind stated which locking means is sturdy, efficient, economical in the space required, and which can be manufactured so as to work well even when the parts are worn to a very considerable extent. In other words, the parts are made and positioned with a degree of tolerance which enables them to work right without requiring any considerable precision either in their

original manufacture or in the maintenance of the parts as they wear. This feature is of particular importance in devices of this character because if an officer finds his arresting irons are not working right, it is usually at the critical time of making an arrest. These mechanisms are not easy to maintain in service because they are subject to rough usage and are scattered in their distribution all over the country. After once being sold, they are hardly ever used or tested by anyone who understands the actual detail mechanism involved. To avoid many difficulties due to these conditions, the present invention has been devised. Other features and objects of the invention will be brought out in the detailed description and annexed claims.

In the drawings:—

Fig. 1 is a plan view of a handcuff assembly such as embodies my invention in one commercial form and in full commercial size;

Fig. 2 is a full sized view of the upper handcuff shown with one of the parallel arms, which carry the lock casing, removed to expose the inside of the lock casing with the locking means in place as it would be when single locked about a normal wrist;

Fig. 3 is a detail view of the locking pawl; Fig. 4 is a detail view of the locking bolt; Fig. 5 is a detail view of the bolt spring; Fig. 6 is a detail view of the bolt pusher; Fig. 7 is a detail view of the key; Fig. 8 is a detail view of the anti-picking device;

Fig. 9 is an end view of the lock casing as seen from the right in Fig. 1; and

Fig. 10 is a detail view of one of the filler pieces forming a part of the lock casing—the one to the right in Fig. 2.

The lock casing as shown, is made up of two filler pieces 1 and 2 which are riveted to and between the ends of parallel arms 3 and 4. The adjacent ends of these filler pieces are spaced a slight distance apart and provided with shoulders to receive and seat the head 7 of the chain swivel 5. The latter is necked down at 6 to pass through the small space between the filler blocks 1 and 2 and is pro-

vided with a shoulder overlying the outer ends of the filler block as the head 7 overlies the inner ends, as shown in Fig. 2. The chain swivel 5 is thus mounted for rotation in the lock casing and the head 7 of this swivel has a function in mounting the locking bolt which will be pointed out later.

The arrangement for the lock casing shown has the advantage of providing a shallow recess bounded by the filler pieces 1 and 2 as 10 end and bottom walls, and the slightly spread outer ends of arms 3 and 4 as side walls. This recess is longer than it is deep, and with its outside dimensions following the general 15 curvature of the arms which carry and help to make up the casing. This is important in avoiding an objectionable bulge outwardly from the bracelet arms as it is found in the commercial forms of handcuffs in general 20 use today. And one of the principal features of my invention is to provide a lock mechanism of eminently suitable construction in such a shallow lock casing to perform well in any or all of the ways desired which 25 will be pointed out.

The mechanism shown mounted in the lock casing may be inserted through the opening in the upper wall. The bolt pusher 8 in the form of a headed pin is inserted from the 30 inside (when the locking arm is out of the way) to lie in the hole through the end wall of filler piece 2 at the right, and with the head within the casing. Then the H-shaped bolt member 9 is inserted horizontally to lie down 35 between the top, bottom, and end walls of the right hand filler piece 2, Fig. 2, in line with the bolt pusher. At the same time the U-shaped bolt spring 11 is carried into place, being mounted loosely (except for its own 40 resiliency) on the upper right hand leg of the bolt member 9. The upper leg of the spring 11 at the end abuts a shoulder stop in the under face of the top wall of filler piece 2, as indicated in the assembled view. The 45 curved end of the spring abuts the end wall of the filler piece 2. The lower free end of the spring has a cam curve or bead portion to snap in one or the other of the recesses 12 and 13 on the under side of the upper right hand leg of the H-shaped bolt. With the 50 spring and bolt in this position, it is clear that when the bolt pusher pin is moved to the left from without the casing, the bolt may be moved to the left and until the spring end 55 snaps in recess 13. The key moves the bolt in the other direction, as will be described. The pin 15 is inserted across the side casing walls after the bolt is slipped in. This pin 15 is 60 positioned to stop any over-throw of the bolt to the left and the end wall stops it to the right. The spring puts a sufficient drag on the bolt to prevent a jarring movement from the positions indicated by notches 12 and 13 65 and so that it will not move except when the

pusher bar or key operates it, no matter how roughly the handcuff is used.

With the bolt in place as described, the coiled pawl spring 16 is inserted in its recess as shown; pawl member 17 is dropped in 70 from the top; and then its pivot pin 18 inserted to properly position the pawl in place. Then the anti-picking device 19 is dropped in and its pivot pin 20 inserted in a similar manner to the pawl assembly.

It will be noted that the lock mechanism is assembled in its casing from the open top and after the casing walls have been assembled and that the pins 15, 18, and 20 are inserted to extend between the side walls of the casing 80 after the walls have been assembled.

My plan is to permanently rivet the parallel arms 3 and 4 and the filler pieces 1 and 2 together to form the lock casing by the rivet pins indicated, to rivet the locking arm 85

21 between arms 3 and 4 for pivotal movement at the end 50 opposite the lock casing and then to finish the cuff as by nickel, chromium or other fine finish, so that the rivet ends will be finished and preferably with all 90

ends smooth and flush with the surface of the arms. As stated, the pins 15, 18 and 20 are inserted with the lock mechanism and the latter is preferably inserted after the cuff is otherwise finished. The ends of such pins 95

may be finished (as by plating) apart from the lock casing, and their fit may be a driving fit with the lock casing and one to avoid marring the finish and they need not be riveted, but their ends are preferably flush with 100

the outside surface of the side walls. As I will explain in the operation of the lock mechanism, it cannot be unlocked, even in the very unusual case where a prisoner might 105

succeed in removing one of the pins 15, 18, and 20, which are held in place by a driving fit. For this reason, these finished pins may be put in after the outside of the lock casing has been completed and polished and the whole lock casing and mechanism may be assembled with its mechanism at the desired time. This I believe to be of considerable 110 advantage in the proper manufacturing operations of such a cuff.

The teeth on the outer rim of locking arm 115 21 are made V-shaped and are shown symmetrical to cooperate with the single symmetrical tooth pawl 17. The arrangement shown is such that when the pawl lies between the teeth of the locking arm the thrust of an unlocking or clockwise movement of the arm 21 is directly normal to the pivot pin 18, and this line passes through the body portion of the pawl 17 and the body portion 120 of the arm 21. This makes for an exceedingly strong construction independently of the strength of the pawl tooth or the teeth on the locking arm and it gives strength even when such teeth are badly worn. The coiled 125

pawl or ratchet spring normally holds the 130

single tooth of the pawl in position to successively engage the teeth of the arm as the latter moves in one direction, which is counterclockwise as shown, and to prevent all movement of the arm in the clockwise or unlocking position as shown.

The provision of a single tooth pawl and of the peripherally arranged V-shaped teeth on arm 21 over an arc having pivot point at 50 as a center, all of the character shown, gives an advantage over the ordinary hook-shaped ratchet teeth and a pawl with multiple corresponding teeth such as has heretofore been used in handcuffs of this general 10 character. The advantage is in the simplicity of manufacture, the added strength, and in addition, the important feature that as the teeth wear there is no change in the strength or desired operation of the parts. 15 The latter feature may be stated as a provision for greater tolerance in the making, assembling, and the wear of the parts without disturbing any desired function for such parts.

20 The anti-picking device 19 is pivoted to cooperate with the teeth of the locking arm like an escapement rocker. That is, the engagement with the ratchet teeth by one end of the rocker, cams the other end into engagement with the teeth and vice versa, so that the arm with its ratchet teeth may readily move by this anti-picking device 19 in either direction without binding on it. But if a thin spring or other lock picking instrument 25 is slipped between the ratchet teeth of the locking arm 21 and its adjacent filler piece 1, in an attempt to get at the pawl 17 to release that, such lock picking instrument cannot possibly get by the anti-picking device, 30 for both ends of the latter cannot be out of contact with the locking arm teeth at the same time to let such an instrument pass by. In fact, such an instrument would itself rock device 19 in such a way as to bind it against 35 full insertion to reach the pawl.

The key, as shown in Fig. 7, is inserted through the hole at the center of the casing and the key has an extended shank or a pin 61 reaching to a bearing in a hole 62 in that 40 face of the lock casing opposite to the one with the ordinary key hole. By turning the key, its radial wing 63 may rub against the lower arm 64 of the pawl lever 17.

This arm 64 normally extends at an angle 45 from the bottom of the lock casing or filler piece 1, sufficiently to permit the lower leg 65 of the bolt to underlie the arm, and in this position absolutely prevent any movement of the pawl arm until the bolt is moved 50 back to the right. Only in the latter position can the key swing the pawl to unlocked position. The engagement is such, between the key and pawl, that a camming wipe of almost 90° is possible while only about half 55 of such angle is normally necessary in the

movement to unlock the pawl. When the key wing is turned way down, the pawl with its spring action to return acts through arm 64 to hold the key in full unlocked position. Or to put it in another way: the key wing 70 has the proper engagement with the pawl cam arm 64 to hold the pawl unlocked when the key is in place and turned way down. This is an advantage because in unlocking a prisoner the officer wants to insert the key 75 and have the key hold the pawl out of locking position after it is turned and without continual hand pressure on the key. Then when the key is removed, the officer wants to have the pawl reset itself and the mechanism arranged automatically and ready for the next prisoner locking operation. The parts are arranged for these functions. The mere removal of the key will reset the lock mechanism without other attention by the 80 officer. After he has unlocked one prisoner, the handcuff is all ready for the next one.

The key can wear and the pawl member can wear to a substantial extent without in any way affecting the desired operation of 90 the parts, since substantially less than a 90° movement is sufficient to unlock the pawl from engagement with arm 21. These parts do not need to be fitted or maintained with any particular degree of precision and 95 this is of great assistance, both in making and in maintaining the cuff for the desired operations. The same general arrangement is made with respect to the key and the key-operated part of the bolt. That is, a broad 100 cam action is provided to give plenty of tolerance under the wear of those parts.

The bolt member is moved to the left by applying the shank or pin extension 61 of the key and pushing on the end of the bolt 105 pusher 8 in hole 30 at the side of the cuff and from without the casing, or a match end might be used for this purpose. The key is not necessary. With the pawl already in locked position, such movement of 110 the bolt extends its lower inner arm 65 in position to underlie the lower cam arm 64 of the pawl. To avoid any necessity for precision in making the casing walls for 115 very accurate sliding operations of the bolt, I provide the following features. The bolt arm 65 meets the pawl arm with a cam action. This forces the bolt downwardly against the top of the head 7 of the chain swivel 5. The head 7 has a shoulder resting on the lock casing. By dressing off the 120 top of this head 7 the parts can be readily fitted and the bolt can be made to slide accurately into underlying position to block the pawl and the recess fit of the bolt with 125 the lock casing may be rather loose and free, which is desirable to avoid friction and expense. While a drag on the bolt movement is desirable, it is better not to have it supplied by friction due to a close fit. Instead 130

I supply a spring to give the desired drag, and this avoids the necessity for accurate workmanship and at the same time gives a better control on the bolt, as well as avoiding any "freezing" of the bolt in one place between desired operations.

When the bolt is moved to double lock the arms it is quite clear that if one tries to pick the lock he will be baffled to a most unusual degree. It would first be necessary for him to move the bolt to the right. To do this, he must find an instrument that will enter the key hole, reach over the outer end of the upper left-hand bolt arm 66, and exert a backward pressure with very little leverage permitted in the distance from the key hole to the bolt end. This is exceedingly difficult with any other instrument than the key, which has a bearing in the key hole to provide for an effective twisting movement to apply the unlocking force as a component of the twisting force. A bendable wire will not be sufficient. In addition to moving the bolt back, it is necessary to release the ratchet pawl, and there is very little leverage for this purpose and what there is must be applied after reaching in from the key hole at right angles to its axis and moving opposite to the bolt unlocking movement.

The bolt is cut away or skeletonized into H-shaped form, made of light weight and held by its drag spring 11 to prevent jarring it from one position to another. The spring and its cam or bead recesses may be made strong enough and at such positions as to hold the bolt against such jarring movements.

It is quite clear that no picking instrument, slipped between the teeth of the locking arm and the upper shelf of the filler piece 2, can release the pawl—primarily because the reach from that end is from the wrong direction. It is also clear that the anti-picking device 19 will prevent picking from the other end.

To prevent any springing apart movement of the arms when in locked position, I preferably provide a circular groove and one that is open ended, in each side face of the locking arm, as shown. On each of the inside faces of the side plates of the lock casing, I provide a projection 72 (shown dotted in Fig. 2), which I locate just above the pawl 17 and with a shoulder to overlie the outer shoulder of the groove 71 in arm 21. This is conveniently done by riveting a headed pin to the casing wall at this point and with the head cut away enough to make a fairly close but frictionless fit with the groove. This enables me to conveniently provide a projection 72 from the lock casing to mate with the groove and one which will not permit any real movement between the arms to pull them apart at the critical point where the

pawl engages the locking arm. These pins may be made up with slightly varying dimensions and the one with the right dimensions to fit a particular cuff and prevent any substantial play in the parts chosen from the lot that gives the best fit. This arrangement avoids the obligation of filing down parts in the final assembly of the cuff, to make a good fit at this critical point.

It is not so good, or so convenient, to have such a projection located elsewhere on the lock casing than where I have shown it, or to provide such a projection as an integral part of the lock casing walls. The latter requires a degree of fine workmanship that is not always attained and it is expensive. My headed pin for this purpose is located by its hole just above the pawl and it is easy to make the head to substantially fill the groove by doing the work before assembling. It should be understood that one of these headed pins is preferably located on each side of the lock casing to substantially fill a groove on each side of the locking arm, which filling is coextensive with the teeth engaged by the pawl as they pass the critical point. When the pawl locks, any prying movement to separate the teeth from the pawl is met by two shoulders provided by parts 72 abutting the two shoulders of the grooves 71 and immediately in line with the attempted movement, but nowhere else. This makes a simple way to further safeguard the lock mechanism with great accuracy, but due to the design rather than the workmanship of the lock fitter.

From the foregoing description, it is clear that I have provided cooperating locking arms with a simple, effective lock mechanism that requires very little space, no objectionable precision work in its manufacture or maintenance under wear, and one which has many other advantages to be seen from its description and use. For example, when used as a handcuff the V-shaped teeth will not catch in the pocket (a serious matter when an officer wants to act quickly and without bungling). The lock casing does not bulge out from the cuff enough to detract from the general circular shape of the bracelets. There is no suggestion from the outside appearance of the cuff what kind of a lock mechanism controls it. The V-shaped teeth may be made smaller and yet stronger than ordinary ratchet teeth; they are self-clearing in that nothing can lodge between them and stay there as with hook-shaped ratchet teeth or ordinary gear teeth.

One of the results and one that I want to emphasize in the character of the above mechanism is that for any or all of my purposes the improved mechanism can be made by ordinary workmen and yet will work as well when new as a lock mechanism made by the most skilled workmen available, and when

worn to a considerable degree will still work just as well, whereas a mechanism that depends upon the high degree of workmanship for its proper operation will ordinarily fail 5 when worn. In other words, the design of my present mechanism wipes out many of the difficulties and much of the expense heretofore met with in devices of this character. The scope of my invention is found from the 10 annexed claims.

What I claim is:

1. In a device for the purpose described, a shallow lock casing having a key hole, a pivoted ratchet lever located between one end 15 of the lock casing and the key hole, a bolt located between the other end of the lock casing and the key hole, said ratchet lever and bolt each having a fork-shaped end providing two 20 prongs adjacent the key hole, said prongs being all arranged to extend in a direction generally parallel to the bottom of the shallow lock casing, one prong of the bolt being proportioned to move into and out of position 25 between the bottom of the lock casing and one prong of the ratchet lever to block or permit movement of the latter, the other prong of the bolt being positioned for a key engagement to move the bolt from the key hole, one 30 prong of the ratchet lever being formed for engagement with the teeth of a ratchet and the other prong being formed for a wiping cam engagement with a key on one side and for said bolt engagement on the other side.

2. A handcuff comprising relatively rotatable bracelet arms pivoted and arranged for complete rotation and a lock mechanism adapted to permit said rotation only in one direction until a wrist or the like is embraced and locked, one of said bracelet arms having 40 extending from its free end a series of symmetrical ratchet teeth on its periphery, said lock mechanism having a casing carried at the free end of that bracelet arm, means complementing the peripherally toothed arm to 45 form the handcuff, and a spring pressed ratchet pawl pivoted in said casing so that a line from its pivot point to any point on the back side of one of the symmetrical ratchet teeth on the toothed arm and engaged by the 50 pawl will be normal to the tooth surface and the pawl engaging surface.

3. A handcuff of the kind described having a lock mechanism comprising an elongated shallow lock casing with a centrally arranged 55 key hole and on one side of the key hole a centrally pivoted rocker arm with a symmetrical ratchet-engaging tooth at each end adapted to rock the lever as a ratchet passes the lock mechanism, and a pivoted spring pressed ratchet pawl having two prongs on the same 60 side of its pivot, one for engaging ratchet teeth and the other lying adjacent the key hole for cam engagement with a key, and on the other side of said key hole a bolt having 65 a key engaging portion adjacent the key hole

and a prong adapted to slide under the key-engageable prong of the ratchet pawl and block its pivoted movements.

4. A lock for handcuffs or the like comprising, a casing having a key hole, a ratchet pawl at one side and a bolt at the other side of the key hole along the length of the casing with their adjacent ends close to the key hole, the ratchet pawl having one prong for tooth engagement with a ratchet and another prong 70 slightly below the former and on the same side of the key hole and for key and bolt engagement to unlock and double lock the ratchet, the bolt having a part for engagement by a key and slightly below that a part to move 75 between the bottom of the casing and the lower latch prong.

5. A handcuff or the like comprising, two relatively pivoted arm members, one having a lock mechanism including a ratchet pawl 80 and the other having ratchet teeth to be engaged by the pawl for locking, cooperating shoulders on said arms, the shoulder means on the toothed arm being coextensive with the teeth and on an arc from the pivot of 85 the arms, the shoulder means on the other arm being relatively short and located adjacent the point where the latch and teeth engage, said last named shoulder means being formed separately as a headed pin with one 90 side of the head flattened to form the short shoulder and then located and riveted to the side of the lock casing adjacent said point.

6. A handcuff including two oppositely arranged semi-circular arms with one pair of ends pivoted together, a series of symmetrical arranged teeth extending backwardly towards the pivot from the free end of one arm over an arc struck from said pivot point, a shallow lock casing extending backwardly towards the pivot from the free end of the other arm, the length of the lock casing on one arm being approximately the same as the extent of the teeth on the other arm and arranged so that when they overlap, the pivoted arms are symmetrical, with the shallow lock casing all lying closely to the circumference of the overlapped arms, a spring pressed pawl pivoted in said lock casing, said lock casing having a shoulder stop 100 in line with the pawl pivot and the point of engagement between said pawl and a tooth on the pivoted arm, said pawl being engageable with said shoulder stop and with said teeth, said toothed arm having a shoulder adjacent to and coextensive with said teeth and arranged on an arc also struck from said pivot point, said shoulders being positioned for one to closely overlie the other whenever said pawl engages said teeth. 110

7. A handcuff including pivoted arm members adapted to come together in bracelet form with opposite ends overlapping, a series of peripherally arranged teeth extending backwardly toward the pivot point from 115

- the free end of one arm on an arc struck from said pivot point, an elongated shallow lock casing depending from the circle of said toothed arc but not on the same member and having closed end and bottom walls, the casing extending generally along an arc struck from the same pivot point, said casing having a depth approximately equal to the general width of the arm members, said toothed arm being adapted to removably form a closed top wall for the lock casing, the extent of said toothed arc being approximately equal to the arc-shaped length of said lock casing, lock mechanism including a pivoted spring pressed pawl in said casing with a tooth to engage successive teeth of said series for a ratchet lock, each successive engagement of the pawl on the back side of the teeth being flat and in a plane normal to the line between the pivot of the pawl and such engagement.
8. A handcuff comprising pivoted bracelet arms, locking means including teeth on the free end of one arm and a lock casing with lock mechanism therein adjacent and carried by the end of the other arm, said lock mechanism including mechanism comprising a small pivoted lever with ends adapted to be alternately engaged and the lever rocked by the passage of the said teeth on the first mentioned arm whereby the latter will have one end or the other of said lever in constant engagement with the teeth thereon to prevent lock picking operations, said lever being located in the lock casing next to the entrance for the first mentioned arm as it swings with respect to the other arm.
9. A handcuff comprising pivoted bracelet arms, locking means on the free end of one arm and a lock casing with lock mechanism therein adjacent and carried by the end of the other arm, said lock mechanism including a lever pivoted within the lock casing and having toothed ends alternately engageable by said locking means to rock the lever and adapted to entrap the end of a lock-picking blade forced between the lock casing and the said free end.

In testimony whereof I have affixed my signature.
